UNITED STATES PATENT OFFICE

164,512

WRENCH FOR SCREW-BACK WATCHCASES

Paul A. Petit, Minneapolis, Minn.

Application February 24, 1951, Serial No. 14,316

Term of patent 7 years

(CL. D54—16)

To all whom it may concern:

Be it known that I, Paul A. Petit, a citizen of the United States, residing at Minneapolis, State of Minnesota, have invented a new, original, and ornamental Design for a Wrench for Screw-Back Watchcases, of which the following is a specification, reference being had to the accompanying drawing, forming a part hereof.

Fig. 1 is a view in perspective of a wrench for screw-back watchcases, showing my new design; and

Fig. 2 is a top plan view thereof.

I claim:

The ornamental design for a wrench for screw-back watchcases, as shown.

PAUL A. PETIT.
